United States Patent Office.

HENRY GETTY, OF BROOKLYN, NEW YORK.

Letters Patent No. 67,037, dated July 23, 1867.

IMPROVEMENT IN PUMPS.

The Schedule referred to in these Letters Patent and making part of the same.

TO ALL WHOM IT MAY CONCERN:

Be it known that I, HENRY GETTY, of the city of Brooklyn, county of Kings, and State of New York, have invented, made, and applied to use a new and improved Double-Acting Lift and Force-Pump for Shallow and Deep Wells, Fire Engines, &c., &c.; and I do declare the following to be a full, clear, and correct description of the same, reference being had to the accompanying drawings, making a part of this specification, and to the letters of reference marked thereon, in which—

Figure 1 is a perspective view of my new double-acting lift and force-pump with escape-valve as used for deep wells.

Figure 2, a longitudinal section of the same, showing the pump cut in half, with the up stroke in red lines.

Figure 3, a view of the hollow ram or plunger detached from the pump, with its piston, valve, and yoke.

In the drawings like parts of the invention are indicated by similar letters of reference.

The nature of my invention consists in dividing the body of the pump into two cylindrical chambers separated by a partition forming a stuffing-box, the upper chamber having a hollow ram or plunger working in it, which is provided with a piston and valve at its lower end working in the lower chamber, which latter is provided with apertures for the admission of air at its upper end, when used for ordinary wells, that the piston may move freely either up or down, or with a valve or valves when used for deep wells, so as to act as a vacuum-chamber to aid in lifting the plunger and pump-rod on its upward motion, the arrangement of the whole being such that it shall operate as a direct-acting lift and force-pump with only two valves, and with a straight passage for the water through it.

To enable those skilled in the arts to make and use my invention, I will now proceed to describe the construction and operation of the same.

C, fig. 2, shows the base of the pump. It is made of cast iron or other suitable material, and is screwed or attached to the lower chamber B of the pump. On the upper side of C, I form a seat for the suction-valve α^2 , with a cage, if a ball-valve is used, to prevent the ball rising too far. Its lower part is screwed or otherwise formed for the attachment of the suction pipe. The lower chamber B of the pump is also formed of cast or wrought iron or other suitable material, and is bored or otherwise made perfectly true inside for the reception of the piston F, which works in it. It is screwed or otherwise formed at its lower part to be attached to the base C, and its upper part is provided with means for attaching it to the partition D. Partition D is formed with a screw at both ends, and provided with an annular shoulder for the chambers A and B to screw up to, or it may be made with a screw its whole length, and let the two chambers abut against each other, so as to form a tight joint. Its centre is bored out for the reception of the hollow ram or plunger P, and has a stuffing-box formed on one side of it for the purpose of keeping the hollow ram or plunger water-tight. The hollow ram or plunger P may be made of brass or other suitable material, and turned true on the outside to fit the hole in partition D. At its lower end I form the piston F, which is firmly attached to it, and inside said piston, opening upward into the hollow ram or plunger, I insert the valve α . Its upper end is left open, and is screwed or otherwise suitably formed for the reception of the yoke Y, to which yoke the pump-rod R is firmly attached in any suitable manner. The upper chamber of the pump A does not need boring out inside, as the hollow ram or plunger does not touch its sides. When used for an ordinary pump, I provide it with a stuffing-box, I, for the rod R to work through, and a spout. When used for deep wells its upper end is suitably formed for the reception of the ascending pipe, through which pipe rod R may work, or I provide it with a branch pipe and air-chamber, and let the pump R work through the top of it, and affix the air-chamber and ascending pipe at its side.

The parts being all put together, as in fig. 2, with the escape-valve S omitted, the operation of the pump is as follows, when used for ordinary purposes: When the pump-rod R is raised it carries the hollow ram or plunger P and piston F up with it. Valve α closes, and the suction-valve α^2 opens, and chamber B is filled with water. The air between the hollow ram and chamber B is at the same time expelled by the rising of the piston through the holes $\alpha\alpha$ in the upper part of chamber B. When the pump-rod R descends, the valve α^2 closes, and the piston F, having double the area of the hollow ram or plunger P, forces the water in chamber B through the valve α and hollow ram or plunger P into chamber A. The hollow ram or plunger P is now filled with water. By the descent of the piston F there would be a vacuum formed between the hollow ram or plunger P and chamber B, but this is prevented by air entering freely through the hole or holes $\alpha\alpha$ in upper part of chamber B.

ber B. When the rod R again ascends, valve α closes, and the hollow ram or plunger P, being now filled with water, acts as a solid ram, and a quantity of air or water of the same area as it is forced out of chamber A through discharge nozzle E. On the rod R again descending, the piston F forces the water which has entered the chamber B through the hollow ram or plunger P, and it is discharged at the nozzle of the pump E. Thus the hollow ram or plunger P becomes alternately a solid ram to force the water out of chamber A, and a hollow tube for the conveyance of the water forced out of chamber B by the piston F into chamber A. When used for deep wells I stop the hole or holes σ σ , and let the down stroke of the pump-rod R by means of piston F create a vacuum in the space between the hollow ram or plunger P and chamber B, which on the upward stroke gives an additional power to it and helps to raise the weight of the rods and water. I insert when thus used a small valve or valves, S, in the hole or holes σ σ in the upper part of chamber B, which valve or valves open outward from said chamber B, and are held firmly down against the pressure of the atmosphere from the inside of said chamber B by a spring or weighted lever, for should any water escape past the piston F into the annular space, the pump would stop working. By the use of the escape-valve S any water which escaped past the piston will be expelled through the escape-valve.

Having thus fully explained my invention, and described the operation of the same, what I claim as my invention, and desire to secure by Letters Patent, is—

The hollow plunger P, acting in its up stroke as a solid ram, and in its down stroke as a water passage, provided with a valve and piston-packing at its lower end, and working in the cylindrical chambers A, B, provided with an annular collar at the point of their junction, forming a stuffing-box, through which said plunger P reciprocates, all arranged and operating substantially as set forth.

HENRY GETTY.
